ANTISLIPPING CANE

William E. Russell and Etta R. Lyon,
Cumberland, Md.

Application January 11, 1935, Serial No. 1,404

8 Claims. (Cl. 135—54)

This invention relates to canes, and its general object is to provide a cane that is primarily designed for use by lame persons, invalids and persons having artificial limbs, to improve their mode of walking as the use thereof will eliminate fear and give them placid confidence, which is not only brought about by the anti-slipping or positive ground engaging qualities of the cane, but also by its equalized dual supporting features.

A further object of the invention is to provide a cane that can be connected to the shoe of the user, therefore it is capable of amply supporting persons having weak or artificial limbs or weak hips or the like, in that the cane is held in the proper position for that purpose at all times.

Another object of the invention is to provide a cane that includes interchangeable ground engaging means, in order to meet existing conditions, with the result the cane can be used on slippery or icy surfaces, as well as in the house, without maring or scratching the floors or the like.

A still further object of the invention is to provide a cane of the character set forth, that is simple in construction, easy to use, inexpensive to manufacture, and extremely efficient in use and service.

This invention also consists in certain other features of construction and in the combination and arrangement of the several parts, to be hereinafter fully described, illustrated in the accompanying drawing and specifically pointed out in the appended claims.

In describing our invention in detail, reference will be had to the accompanying drawing wherein like characters denote, like or corresponding parts throughout the several views, and in which:

Figure 1 is a perspective view illustrating our cane in use.

Figure 2 is a side view of the cane with parts in section and illustrating the application of ground penetrating inserts thereto.

Figure 3 is a sectional view illustrating the application of the shoe carrying attachment.

Figure 4 is a top plan view of said attachment.

Figure 5 is a fragmentary view of the resilient, shock absorbing, anti-slipping insert in applied position.

Referring to the drawing in detail, the reference numeral 1 indicates the body of the cane which is of the usual construction that is provided with a curved handle portion 2.

The lower end of the body 1 terminates into

a reduced threaded end 3. Arranged adjacent to the lower end of the body 1 is a bracket 4 that includes an elongated transversely curved section 5 that follows the curvature of the body 1 and is provided with a plurality of openings to receive securing means such as screws 6 for fixing the bracket to the body as clearly shown in Figure 2. Extending from the section 5 at a downward inclination is a socket 7 which is preferably formed integral with the section 5 and is disposed in a direction opposite from that of the handle portion 2.

Extending from the bracket and having one of its ends secured in the socket of the section 7 so as to follow the inclination thereof is a rod 8 that terminates in a plane above the lower end of the body 1 when the latter is disposed in a true vertical line as clearly shown in Figure 2. The free end of the rod 8 is likewise reduced and threaded.

When our cane is to be used on slippery and icy surfaces, ground penetrating means is employed for both the rod 8 and the body 1, and ground penetrating means includes a conical portion 9 that terminates in a penetrating free end and has formed therewith a threaded ferrule 10 to receive the reduced threaded ends of the rod 8 and body 1, as shown in Figure 2. However, when our cane is to be used on dry surfaces and especially within a house, we employ elastic shock absorbing anti-slipping ground engaging means, each of which includes a threaded ferrule 11 to be secured to the ends of the rod 8 and body 1 and a socketed lower end to receive a tip of elastic material, such as rubber, the tip being indicated by the reference numeral 12.

While the cane as above described can be used in the customary manner, and will perform its intended function to prevent slipping on any surface and can be used with greater ease and creates confidence in the user, in that fear will be eliminated, we also employ means for connecting the cane with the shoe of the user, so that the cane will be properly positioned with respect to the limb to amply support the same at all times. This feature is extremely advantageous for use with artificial limbs, and persons having weak limbs and hips, in that the proper support is present when needed.

The shoe connecting means includes an angle bracket provided with a horizontal arm 13 which is to be riveted to the sole of a shoe as shown in Figure 3, and a vertical arm 14 that has secured thereto a sleeve 15 which is preferably

made from a strip of leather rolled upon itself as clearly shown in Figure 4. The sleeve 15 is tapered slightly toward its lower end and is designed to receive the lower portion of the body of the cane, as clearly shown in Figures 1 and 2.

From the above description and disclosure of the drawing, it will be obvious that we have provided a cane that not only prevents slipping, but is capable of producing ample support to the limbs and other parts of the user, especially while walking. This feature is mainly brought about by the rod 8, which due to its relative position with respect to the body 1 and the length thereof, as shown in Figure 2, it cooperates with the body 1 in not only providing a dual support, but the support is continuous, due to successive action of the rod and body, to relieve leg pressure on the foot prior to taking a step forward and during the time the foot is being lifted, and it supports the user during the step. It is of course understood that this action is automatic which is brought about by natural coordination of the hand of the user with the movement of the limb, and the fact that the body of the cane is retained associated with the limb by its connection with the foot through the instrumentality of the shoe attachment.

While we have illustrated one of our canes in use, it will be apparent that two canes can be used and will not only accomplish the function of crutches, but are preferable thereto, in view of the added advantages, as well as the fact that crutches induce what may be termed an invalid complex which is not present when use is made of our canes.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:

1. A cane comprising a body, means extending from said body and cooperating therewith to provide dual ground engaging means for successive engagement with the ground to produce an equalized continuous supporting means for the user when walking.

2. A cane comprising a body, means extending at an inclination from said body and terminating in a plane above the lower end of the body when the latter is in a true vertical line, and said means cooperating with the body to provide dual ground engaging means for successive engagement with the ground to produce an equalized continuous supporting means for the user when walking.

3. A cane comprising a body, a bracket secured to said body, means secured in said bracket and extending at an inclination with respect to the body, said means cooperating with the body to provide dual ground engaging means for successive engagement with the ground to produce an equalized continuous supporting means for the user when walking.

4. A cane comprising a handled body, a bracket secured to said body, means secured in said bracket and extending at an inclination with respect to said body, said means terminating above the lower end of the body when the latter is disposed in a vertical line, said means cooperating with said body to provide dual ground engaging means for successive engagement with the ground to produce an equalized continuous supporting means for the user when walking, and means for slidably and detachably connecting the body to the shoe of the user.

5. A cane comprising a body, a bracket secured to said body, means extending from said bracket and disposed at an inclination with respect to said body for cooperation therewith to provide dual ground engaging means for successive engagement with the ground to produce an equalized continuous supporting means for the user when walking, and said ground engaging means being adapted to interchangeably receive and have detachably secured thereto either yieldable ground contacting means or ground penetrating means.

6. A cane comprising a body, means extending from said body and cooperating therewith to provide dual ground engaging means for successive engagement with the ground to produce an equalized continuous supporting means for the user when walking, and ground penetrating means detachably connected to the lower end of the first mentioned means and the body.

7. A cane comprising a body, means extending from said body and cooperating therewith to provide dual ground engaging means for successive engagement with the ground to produce an equalized continuous supporting means for the user when walking, and yieldable means detachably connected to the lower end of the first mentioned means and the body.

8. A cane comprising a body, means extending from said body and cooperating therewith to provide dual engaging means for successive engagement with the ground to produce an equalized continuous supporting means for the user when walking, means for detachably connecting the lower end of the body to the shoe of the user for slidable movement and ground contacting means detachably secured to the lower ends of the first mentioned means and the body.

WILLIAM E. RUSSELL.
